UNITED STATES PATENT OFFICE.

SIDNEY H. SHORT, OF CLEVELAND, OHIO.

TROLLEY OR COLLECTOR WHEEL FOR ELECTRIC RAILWAYS.

SPECIFICATION forming part of Letters Patent No. 427,628, dated May 13, 1890.

Application filed March 18, 1890. Serial No. 344,328. (No model.)

To all whom it may concern:

Be it known that I, SIDNEY H. SHORT, of Cleveland, in the county of Cuyahoga and State of Ohio, have invented certain new and useful Improvements in Trolley or Collector Wheels for Electric Railways; and I do hereby declare the following to be a full, clear, and exact description of the invention, such as will enable others skilled in the art to which it appertains to make and use the same.

My invention has reference to trolley or collector wheels, notably adapted for use in connection with electric railways in which a line or lines of conductors are arranged parallel to and extending along the line of travel. In such railways a wheel or wheels of conducting material are made to travel with the motor-car and in contact with the line or lines of conductors to convey the current from the same to the electric motor on the car. The rails of the road may themselves constitute the line-conductors or one of them, and a collector-wheel may then travel in contact with such rail or rails; or one or more collector-wheels may be used for conveying the current from an underground or overhead conductor to the motor-car. More especially in the latter case are the collector-wheels exposed to the weather, and if made of metal, as has heretofore universally been done, these collectors, more especially when not in active use, become soon oxidized, whereby the electric contact is impaired and considerable sparking is thereby occasioned. The rapid movement of the collector-wheel in contact with the line-conductor is also accomplished by a loud and disturbing noise, and the expense of such metallic collector-wheels is considerable.

The object of my invention is to avoid the defects and inconveniences pointed out; and I accomplish this result by making the body of the collector-wheel of carbon, which is not injuriously affected by weather, runs noiselessly over the line-conductor, and by reason of the good and intimate contact it makes produces no sparking. In addition thereto my improved collector wheel or roller does not wear the line-conductor to the same extent as a metallic wheel, and is manufactured with ease and at much less cost than the latter.

According to the form and location of the

line-conductor in connection with which the collector-wheel is to be used, the form of the same and the manner of mounting it upon a trolley-arm will change. I am, therefore, not confined to a particular shape of collector-wheel nor to its use in connection with any particular line-conductor.

In the accompanying drawings I have illustrated in Figure 1 an elevation of a collector-wheel of my improved construction mounted upon a trolley-arm and bearing upon an overhead line-conductor, and in Fig. 2 a vertical section of the collector-wheel and overhead conductor on line *x x*, Fig. 1.

Like numerals of reference indicate like parts all throughout the drawings.

The body 1 of my collector-wheel is made of a carbonaceous mixture of the kind known as "plastic" carbon or "Bunsen" carbon, which is now universally used for the manufacture of electrodes, rods, or pencils for electric-arc lights, and for batteries. Preferably the carbon which I use is of fine grain and of uniform density, like the well-known Carré or Brush carbons found in the market. By preference also the wheel is formed in suitable molds under great pressure, so that the surface becomes very much denser than the interior, and constitutes in effect a very hard skin, which envelops the body of the wheel. While this is the preferable construction of the body of the contact-wheel, I am not absolutely confined to the same, since it may be made by shaping a solid disk of carbon by means of suitable cutting or grinding tools. In this case the interior comparatively porous portion of the carbon would be exposed; but, as will presently appear, the contact-surface of the wheel will be condensed, either in the process of manufacture or by use.

The circumferential surface of the wheel is shaped to adapt the same to the shape of the line-conductor. In the drawings, the line-conductor is shown as a cylindrical wire 2, and the wheel is therefore formed with a wide groove 3, the bottom 4 of which constitutes the contact-surface, and this contact-surface becomes condensed and highly polished by use, whether the groove has been formed in the mold or by cutting. In either case, however, it may be polished in the course of manu-

facture by suitable tools in a manner similar to that practiced in polishing carbon electrodes for microphones.

A bushing or axle box 5, of brass or other suitable metal, is inserted in an axial perforation in the wheel, and this bushing is formed at one end with a circular flange 6, which covers part of one face of the wheel, while another similar flange 7 is fitted to the other end of the bushing and against the other face of the wheel.

The two flanges or face-plates 6 7 are secured to the wheel by bolts 8 8, and the wheel is mounted upon a trolley-arm 9 in any ordinary or approved manner.

Having fully described my invention, what I claim as new, and desire to secure by Letters Patent, is—

1. A trolley or collector wheel of carbon, substantially as described.
2. A trolley or collector wheel of Bunsen carbon, substantially as described.

3. A trolley or collector wheel of carbon, having its contact-surface condensed, substantially as described.

4. A trolley or collector wheel of carbon, having its contact-surface polished, substantially as described.

5. A trolley or collector wheel of carbon, provided with a metallic axle-box, substantially as described.

6. A trolley or collector wheel of carbon, provided with a metallic axle-box and metallic face-plates, substantially as described.

In testimony whereof I have signed this specification in the presence of two subscribing witnesses.

SIDNEY H. SHORT.
